AUXILIARY CLOSURE FOR DOORWAYS OF FREIGHT CARS

Filed Sept. 26, 1922

2 Sheets-Sheet 2

Inventor:
Wallace W. Booth,

By his Attorney, Leo P. Niemi

UNITED STATES PATENT OFFICE.

WALLACE W. BOOTH, OF BROOKLYN, NEW YORK.

AUXILIARY CLOSURE FOR DOORWAYS OF FREIGHT CARS.

Application filed September 26, 1922. Serial No. 590,621.

To all whom it may concern:

Be it known that I, WALLACE W. BOOTH, a citizen of the United States, and a resident of the borough of Brooklyn, county of 5 Kings, city and State of New York, have invented certain new and useful Improvements in Auxiliary Closures for Doorways of Freight Cars, of which the following is a specification.

- 10 My improvements relate to means for temporarily and internally closing and sealing the doorways of freight cars when the latter are used for the transportation of grain, or any other product or material consisting of relatively small particles or component parts, in bulk,—i. e. any substance that will "flow" by gravity, including the smaller grades of coal, etc.
- 15 My objects are to avoid the labor and expense heretofore involved in the preparatory "coopering" or boarding up of such doorways, and the subsequent labor and waste involved in the removal and discarding of such "cooperage"; to facilitate the operations both of applying and dispensing with my substitute for such cooperage; to attain an effective sealing in of the mobile material held in bulk in the car so that there can be no leakage thereof during storage or transit; and to accomplish these results by comparatively simple and inexpensive means, intact and transferable for use as required.

20 To this end my invention consists in the specific construction, combination and arrangement of component parts and appurtenances herein described and claimed; distinctive features consisting in the provision of cam-actuated and controlled locking plates; the duplex character of the cams employed in relation therewith; in a supplementary slidable miniature emergency door formed in my temporary sealing panel and provided with a rear seal plate; and in certain incidental minor details of construction, all as hereinafter fully set forth.

25 In the accompanying drawings, I illustrate a practical embodiment of the essential features of my invention as applied to a freight car, of any ordinary or desired construction, provided with the usual side doorways and slidable doors, with the understanding however, that I do not necessarily confine myself to the identical form and construction of minor parts and details, since modifications or substitution of equiva-

lent mechanical expedients may obviously be resorted to with like results, and without departing from the spirit and intent of my invention in this respect. 60

Fig. 1, is a diagrammatic representation of a side elevation of a freight car, to the doorway of which my auxiliary closure panel is applied:

Fig. 2, is a front elevation of my auxiliary 65 closure panel:

Fig. 3, is an elevation of one of the vertical edges of my closure panel, looking in the direction indicated by the arrow *x* between said Figs. 2 and 3: 70

Fig. 4, is a transverse vertical section taken upon the plane of line 4—4, Fig. 2:

Fig. 5, is a horizontal section taken upon the general plane of line 5—5, Fig. 2, but upon a larger scale, and with the central 75 portion of the panel broken away:

Fig. 6, is a sectional detail upon an enlarged scale, taken upon the plane of line 6—6, Fig. 2:

Fig. 7, is a perspective view of one of the 80 duplex cams used to control the slidable locking plates:

Fig. 8, is an edge elevation of said duplex cam:

Fig. 9, is a front elevation, broken away 85 in parts, of one of the slidable locking plates:

Fig. 10, is an elevation, upon a larger scale, of a portion of one of said locking plates: 90

Fig. 11, is a transverse section taken upon plane of line 11—11, Fig. 10.

Fig. 12, is a rear or inside elevation of the emergency door, looking in the direction of the arrow *y*, shown in Fig. 4: 95

Fig. 13, is a sectional detail of one of the door jambs, etc., as shown in Fig. 5, illustrating a modification in the cam mounting means;

Fig. 14, is a sectional detail, taken upon 100 plane of line 14—14, Fig. 3, of one side portion of my closure panel;

Fig. 15, is a sectional detail taken upon the plane of line 15—15, Fig. 2.

K, represents an ordinary freight car, 105 formed with the door way *k*, closable by means of the usual slidable external door *k'*,—*j*, *j*, being the door way jamb posts or members.

Heretofore it has been customary, in preparing a freight car for a load of grain or other loose mobile material in mass, to board 110

up and close the door way to a greater or less extent in height, by positioning planking horizontally across said door way and nailing the same to the interior sides of the 5 jambs, j , j , thereby constituting what is known in freight parlance as "cooperage". This involves considerable expenditure of 10 time and labor, and even when done carefully results in interstices and crevices 15 through which the material is apt to sift and be lost, as the outer door k' , of the car affords little or no protection in this respect. Furthermore, after serving their purpose, the boards constituting the "cooperage" closure 20 have to be wrenched loose or chopped away and discarded, being practically a total loss in this particular, as well as an element of danger on account of protuberant nails, splinters, etc., not to mention the inconvenience 25 of the operation of dislodgement of this primitive form of closure, and the time and labor consumed thereby.

Hence the main object of my invention is the production of a closure panel of permanent structure, but designed for temporary use upon occasion as an auxiliary to the usual slidable car door,—a device that can be quickly and conveniently applied to or removed from the doorway, the only permanent addition to the car itself being the provision of the existent door jambs j , j , on their inner sides with auxiliary jamb flanges j' , j' , as shown more particularly in Fig. 5 of the drawings, these auxiliary jamb flanges, j' , j' , consisting preferably of strips of wood nailed or otherwise permanently attached to the usual door-jamb j , j , of which they become a permanent part, their projection beyond said original door-jamb j , j , being but slight, and insufficient to interfere with the use of the car for other and ordinary purposes.

My auxiliary closure panel A, comprises a series of horizontally disposed rabbet-jointed boards a , a , held together in alignment by transverse vertical cleats a' , a'' , three of which are preferably provided, i. e.—a central medial cleat a' , and two marginal cleats a'' , a'' , adjacent to the side edges of the panel, as shown more particularly in Fig. 2, of the drawings. These cleats are positioned on what may be designated as the exterior surface of the panel. On the other or inner side of the panel, the lower portion thereof is provided with longitudinal reinforcement battens a^3 , a^4 , as shown particularly in Figs. 3 and 14, of the drawings, the function of these battens being to strengthen and fortify the auxiliary panel at and along the area of greatest strain when in use as a retainer for a maximum load of mobile material within the car. The upper edge a^3' , of the upper batten a^3 , is chamfered or bevelled as shown in Fig. 3, to facilitate the settling and descent of the

grain or other mobile material and relieve frictional contact therewith when the door is being raised, so as to permit the material to flow freely underneath. This construction also facilitates the discharge of 100 mobile material through the emergency door way e^x , when raised.

The emergency door e , is slidably supported between ways e' , e' , (see particularly Fig. 15) and is protected on its inner side 75 by a guard plate g , formed with an inturned lower lip g' , which bears lightly against the inner surface of the door e , and prevents clogging by the intrusion of load material between said door e , and said guard plate g , and also by relieving the door of load pressure, insuring the operativeness of this means of delivery, or sampling of goods or material en route.

The lower member a^x , of the series of horizontally disposed rabbet-jointed boards a , a , constituting the body of my auxiliary closure panel A, and which member I hereinafter designate as the sill-board a^x , is of greater area in cross section than the boards a , a , above; and has bolted to it, as indicated in Fig. 6, particularly, (or otherwise rigidly secured to the sill board a^x) a longitudinal metallic shoe, s , preferably rectangular in cross section, which not only affords 90 a perfect line of floor contact, but also protects the bottom of the panel A, against injury when the panel is raised by a crow-bar or similar implement used in effecting a preliminary opening between the lower part of the panel A, and the floor of the car K. The upper inner surface a^x' , of the sill board a^x , is bevelled so as not to impede the flow of load material by reducing frictional contact therewith when the panel A, is raised.

B, B, are bolt plates mounted on the marginal cleats a^2 , a^2 , as shown more particularly in Figs. 2, 3, and 5, and 14 of the drawings. They are held laterally slidable on said cleats a^2 , a^2 , by means of headed studs 110 or screws b , b , passing through transverse slots b' , b' , formed for the purpose, at suitable distances apart, in said bolt plates B, B, as shown more particularly in Figs. 2 and 3, of the drawings. Figs. 9 and 11 inclusive, 115 show one of these bolt plates B, in detail, by reference to which it will be seen that, besides the transverse slots b' , b' , each plate B, is formed with a rectangular flange b^2 , on one edge extending the full length of the 120 plate, and also with thrust shoulders b^3 , b^3 , adjacent to the other edge of the plate. Between these thrust shoulders b^3 , b^3 , and the rectangular longitudinal flange b^2 , the plate is formed with transverse elongated 125 openings b^4 , b^4 , to accommodate, in each case, a cam fulcrum f , on which a duplex lock cam D , is rotatably mounted. These fulcrum openings, b^4 , b^4 , as do the transverse slots b' , b' , provide for the lateral recipro- 130

cation of the bolt plates B, B, when actuated by the duplex cams D, as hereinafter set forth.

Two or more of these lock cams D, are provided for each bolt plate B, and each may be designated as a duplex cam, in that it not only functions to thrust the bolt plate B, in either direction, into or out of engagement with an auxiliary jamb j' , of the door-way, but also to clamp said bolt plate B, tightly and rigidly against said jamb j' , and also against the cleat a^2 , on which said plate B, is mounted.

Fig. 7, shows one of my duplex locking cams D, in perspective, by reference to which it will be seen that it is formed with an inner eccentric or thrust portion d , for peripheral contactual engagement on one flange of the plate B, with the rectangular flange b^2 , and also with a thrust shoulder b^3 , on the other edge of said lock plate B, said cam D, being also formed with a lateral wedge section d' , the function of which is to supplement the action of the thrust eccentric d , by clamping the lock plate B, rigidly in contactual engagement with both the marginal cleat a^2 , and the auxiliary jamb flange j' , thereby also drawing the door panel tightly against the jamb j' , and maintaining a positive seal on both sides thereof, as heretofore stated, and as shown more particularly in Figs. 5 and 13, of the drawings.

In this clamping operation the head f' , of the fulcrum bolt f , performs an important function in that it affords the requisite fixed resistance for the wedge d' , in forcing the adjacent portion of the lock plate B, against the opposed surfaces of the jamb-flanges j' , and cleats a^2 ,—it being understood of course, that the several cams D, D, are facsimiles, and that the operations above set forth apply to each cam and its area of action.

In order to facilitate the rotative movement of each cam D, on its fulcrum bolt f , even when the parts are in locked relationship as above set forth, I interpose a metallic bearing sleeve i , between said bolt f , and the hub of the cam D, as shown in Fig. 5, and imbed a metallic washer w , in the face of the cleat a^2 , to form a stress-bearing surface for one end of said sleeve i , the other end of the latter bearing against the head f' , of the fulcrum bolt f ; or the bearing sleeve i , may be dispensed with, as in the modification shown in Fig. 13, in which case the fulcrum bolt f , is formed with a cam-bearing surface f^2 , of larger diameter than the threaded end of the bolt f , so as to form a shoulder f^{21} , to bear against the stress washer w , and thereby relieve the hub of the duplex cam from undue pressure, so that it may be conveniently manipulated as desired.

It will be noted that the flange connecting the main portion of the plate B with the

flange b^2 also constitutes a shoulder with which the thrust plate d is engageable.

By the provision of my auxiliary closure panel thus formed and equipped, I am enabled to materially shorten the time and labor involved in both loading and unloading a freight car with mobile material of the character designated, representing in fact a proximate gain of nine tenths as compared with the old method of "coopering" up a door way, and the final destruction of such cooperage. Furthermore, it must be remembered in this connection, that my auxiliary panel is of unitary and permanent structure, and may be used repeatedly, the only alteration in the car door-way being the addition of the supplementary jamb j' , which in no wise interfere with the use of the car without my auxiliary panel.

Finally, my auxiliary panel, and method of use and manipulation, affords a perfect double seal in so far as the mobile contents of the car is concerned; and the emergency door in said panel affords a safe means of delivery en route, into sacks or wagons on sidings at points other than terminals.

What I claim as my invention and desire to secure by Lettets Patent is,

1. In combination with the side door-way of a freight car provided with auxiliary jamb flanges, an auxiliary closure panel therefor, comprising a series of longitudinal boards, transverse marginal cleats uniting the same, laterally slidable shouldered bolt plates mounted on said marginal cleats, and a plurality of duplex cams fulcrumed on the panel, each duplex cam formed with an eccentric thrust member engageable with the shoulders of the respective plate to move said plate to and from a position overlying the respective jamb flange and with a wedge member to bind said plate and flange into close engagement for the purpose and substantially in the manner set forth.

2. In combination with the side door-way of a freight car provided with auxiliary jamb flanges, an auxiliary closure panel therefor, comprising a series of longitudinal boards, transverse marginal cleats uniting the same, laterally slidable shouldered bolt plates mounted on said marginal cleats, and a plurality of duplex cams fulcrumed on the panel each duplex cam formed with an eccentric thrust member engageable with the shoulders of the respective plate to move said plate to and from a position overlying the respective jamb flange and with a wedge member to bind said plate and flange into close engagement, together with longitudinal reinforcement battens positioned on the lower inner side of said panel, for the purpose and substantially in the manner set forth.

3. In combination with the side door-way of a freight car provided with auxiliary

- the respective jamb flange and with a wedge member to bind said plate and flange into close engagement, together with an emergency door and exit formed in said panel, and a rear shield plate contacting with said emergency door, substantially in the manner and for the purpose set forth. 35
5. In combination with the side door-way of a freight car provided with auxiliary jamb flanges, an auxiliary closure panel therefor, comprising a series of longitudinal boards, transverse marginal cleats uniting the same, laterally slideable shouldered bolt plates mounted on said marginal cleats, and a plurality of duplex cams fulcrumed on the panel each duplex cam formed with an eccentric thrust member engageable with the shoulders of the respective plate to move the shoulders of the respective plate to move 40
- 10 said plate to and from a position overlying the respective jamb flange and with a wedge member to bind said plate and flange into close engagement, together with a sill board forming the bottom of the panel, and a metallic shoe extending longitudinally along the bottom of said sill-board, for the purpose and substantially in the manner set forth. 45
4. In combination with the side door-way of a freight car provided with auxiliary jamb flanges, an auxiliary closure panel therefor, comprising a series of longitudinal boards, transverse marginal cleats uniting the same, laterally slideable shouldered bolt plates mounted on said marginal cleats, and a plurality of duplex cams fulcrumed on the panel each duplex cam formed with an eccentric thrust member engageable with the shoulders of the respective plate to move the shoulders of the respective plate to move 50
- 20 said plate to and from a position overlying the respective jamb flange and with a wedge member to bind said plate and flange into close engagement, together with an emergency door and exit formed in said panel, substantially in the manner and for the purpose set forth. 55
